CLAIM

The ornamental design for the combined aerator and sod plugger, as shown and described.

DESCRIPTION

FIG. 1 is a front elevational view of the combined aerator and sod plugger showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The shaft portion of the claimed design is shown broken away in FIGS. 1-4 to indicate indeterminate length.
